(57) **CLAIM**

We claim the ornamental design for a rear projection television, as shown and described.

DESCRIPTION

FIG. 1 is a front perspective view of a rear projection television of the present invention;
FIG. 2 is a rear perspective view thereof;
FIG. 3 is a front view thereof;
FIG. 4 is a first side view thereof;
FIG. 5 is a rear view thereof;
FIG. 6 is a second side view thereof;
FIG. 7 is a top view thereof; and,
FIG. 8 is a bottom view thereof.

The ornamental design which is claimed is shown in solid lines in the drawings. Any broken lines in the drawings are for illustrative purposes only and form no part of the claimed design.
